VAPORIZING TYPE OIL BURNER

John Thomson, Oakland, Calif.

Application June 26, 1948, Serial No. 35,309

7 Claims. (Cl. 158—91)

1

This invention relates to improvements in oil burner units.

An object of the present invention is the provision of a unit for burning oil more efficiently than the known devices for this purpose, and without the formation of carbon.

A further object is the provision of an oil burner unit in which the oil and air supply thereto are preheated.

A further object is the provision of an oil burner unit in which the air is directed on to the surface of the oil in order to form a comparatively large volume of carbon monoxide at this point in order to obtain increased efficiency from the hydrogen content of the oil by keeping the formation of water to a minimum.

A still further object is the provision of an oil burner unit in which a pilot light may be burned without the formation of carbon.

A further object is the provision of a device of the nature described in which automatic electric ignition may be employed without danger of the electrode being burned by excessive heat.

With the above and further objects in view, the present invention consists essentially of an oil burner unit comprising an open-topped combustion chamber having perforated side walls diverging towards the top thereof, means for supplying air to the chamber through the perforations of its side walls, a sump at the bottom of the chamber, and means for supplying oil to the sump, as more fully described in the following specification and illustrated in the accompanying drawings, in which:

Figure 1 is a plan view of the oil burner unit.

Figure 2 is a cross section through the unit.

Figure 3 is a longitudinal section through the unit, and

Figure 4 is a section through a sump according to this invention with which automatic electric ignition is used.

This device consists of an open-topped combustion chamber 10 having side walls 11, each of which is formed with a plurality of perforations 13. The sections 15 of these side walls converge to a point 16 spaced above the bottom 17 of the combustion chamber, and the sections 18 diverge from said point towards the top of the chamber. The perforations in the sections 15 are directed towards the bottom 17, whereas the perforations of the sections 18 are directed inwardly and upwardly in relation to the combustion chamber. The chamber is closed by end walls 20 which may be vertical or they may diverge towards the top of the chamber, as shown. The angle of the

2

sections 15 may range approximately from 45 degrees to 60 degrees, while that of the sections 18 may be angular for 45 degrees to 80 degrees from the horizontal.

- 5 A sump 25 is mounted at the bottom of the chamber 10 centrally thereof. This sump preferably projects into the chamber above the bottom 17, and is formed with one or more openings 26 in its wall above or in line with said bottom. 10 If desired, a plurality of openings 27 may be drilled in the wall of the sump and directed downwardly towards the sump bottom. Walls 28 extend along opposite sides of the sump projecting into the combustion chamber. It is highly desirable to form a well 29 at the bottom of the sump, said well being of smaller cross-sectional area than the sump itself. A pipe 30 is provided for directing oil from a suitable source of supply, not shown, to the sump and its well immediately beneath the bottom of the combustion chamber. It is preferable to have this pipe extend along the bottom for some distance before reaching the sump. The oil level in the sump is controlled by the usual equipment for this purpose, and as this equipment does not form part of the invention, it need not be described herein.

- Suitable means is provided for directing air through the perforations 13 of the side walls 11 into the combustion chamber. A closed air box 30 is provided for this purpose. The combustion chamber is mounted in this box and opens outwardly through the top thereof, said chamber being spaced from the walls 36 and the bottom 37 of the box. For convenience of manufacture, 35 the side walls 11 of the chamber may be formed with flanges 38 at the top thereof adapted to overlap the top 40 of the box, to which they are secured in any suitable manner.

- Air is supplied under low pressure to the box 40, from which it passes through the perforations 13 into the combustion chamber. A relatively large pipe 45 extends longitudinally of the box 35 below the bottom thereof. The end 46 of this pipe is closed, while its opposite end 47 is connected to a small blower unit, not shown, which is operated in the usual manner. A vertical baffle 48 extends longitudinally of the pipe, and conduits 50 are located along each side of the pipe and extend upwardly through the bottom 37 into the box 35 on each side of the combustion chamber near the bottom thereof. These conduits extend substantially throughout the length of the chamber and communicate with the interior of the pipe 45 at 51, and at their upper ends with 55 the interior of the air box at 52. A sloping baf-

file 53 is located between the end 52 of each conduit and the section 18 of the adjacent wall 11, said baffle being substantially parallel with and spaced from said wall. For convenience of manufacture, the baffles 53 may be formed integrally with the bottom 17 of the combustion chamber. In this case, the side walls 11 and the end walls 20 of the chamber are formed separately from the bottom thereof, and the bottom is secured to the lower edges of said walls in any suitable manner, such as by welding. 10

In order to start this burner, a small amount of oil is directed into the bottom of the sump through the pipe 39. This is ignited and when the surrounding parts are heated, the oil is then turned on. It is preferable to turn the oil on gradually. The oil fills the sump and runs out through the openings 26 on to the bottom 17 of the combustion chamber, where it is converted into vapour which burns in said chamber. The cross-sectional area of the combustion chamber gradually increases towards its top in order to accommodate the increasing volume of gases as they rise from the bottom to the top of the chamber. These gases mix with air entering the chamber through the perforations 13 and burn with a very hot flame. As the perforations in the sections 15 of the side walls are directed downwardly, the air passing therethrough is directed on to the surface of the oil on the bottom of the chamber. This unites oxygen and carbon at the ignition point of the oil at comparatively low temperatures, resulting in the formation of a comparatively large amount of carbon monoxide at said point, thereby increasing the efficiency of the device. Large amounts of carbon monoxide at the primary combustion point result in increased efficiency from the hydrogen content of the oil as the formation of water is kept to a minimum due to immediate higher temperature when the secondary air is introduced through the sections 18 of the side walls.

The air passes along the pipe 45 and the conduits 50, from which it is directed into the air box 35 along the opposite sides of the combustion chamber. The baffles 53 ensure a fair distribution of the air through the perforations 13. The air box and perforated walls of the combustion chambers permit maximum air input at low pressures, thus keeping air temperatures down. Furthermore, the air is preheated in the box before entering the combustion chamber.

According to this invention, the oil is supplied to the bottom of the sump. A pilot light may be provided in the customary manner, that is, when the oil is shut off, a small amount is allowed to trickle through the feed pipe in order to keep a small flame burning. In this case, the flame is in the sump at the bottom thereof, and a limited amount of air is supplied thereto through the openings 27. The sump wall protects the flame from excess air and it retains sufficient heat to keep the pilot light burning with carbon-free flame.

Automatic ignition is shown in Figure 4. An igniting rod 60 of any well-known automatic system projects into the sump. When oil is turned up for high heat, this rod is immersed in oil preventing it from being burned out.

I claim:

1. An oil burner unit comprising a closed air box, a combustion chamber having side walls mounted in the box and opening outwardly through the top thereof, said walls converging to a horizontal plane spaced above the bottom of

the chamber and diverging from said plane towards the chamber top, and said chamber being spaced from the walls of the box, conduits extending through the box on each side of the combustion chamber, said conduits communicating at one of their ends with the interior of the box, means for supplying air to the conduits, a sloping baffle between the end of each conduit and the adjacent diverging section of the combustion chamber side wall, each of said baffles being substantially parallel with and spaced from the adjacent wall, a sump at the bottom of the chamber, and means for supplying oil to the sump.

2. An oil burner unit comprising a closed air box, a combustion chamber having side walls mounted in the box and opening outwardly through the top thereof, said walls converging to a horizontal plane spaced above the bottom of the chamber and diverging from said plane towards the chamber top, and said chamber being spaced from the walls of the box, conduits extending upwardly through the bottom of the box on each side of the combustion chamber near the bottom thereof, said conduits extending substantially throughout the length of the chamber and communicating at their upper ends with the interior of the box, an air supply pipe extending between the conduits, said conduits communicating at their lower ends with the interior of the pipe, a vertical baffle extending longitudinally of the pipe, a sump at the bottom of the chamber, and means for supplying oil to the sump.

3. An oil burner unit comprising a closed air box, a combustion chamber having side walls mounted in the box and opening outwardly through the top thereof, said walls converging to a horizontal plane spaced above the bottom of the chamber and diverging from said plane towards the chamber top, and said chamber being spaced from the walls of the box, conduits extending within the box on each side of the combustion chamber near the bottom thereof, a sump at the bottom of the chamber, and having a part at the sides thereof extending above the chamber bottom, said part having a plurality of openings directed downwardly towards the sump bottom, and means for supplying oil to the bottom of the sump.

4. In an oil burner, a housing provided with a burner throat in the upper portion and having opposing elongated side walls and opposing end walls defining with a substantially flat bottom wall a combined vaporization and combustion chamber, said side walls having lower sections extending upwardly from said bottom in convergent relation and upper sections extending upwardly from said lower sections toward said throat in angular relation to said lower sections, an oil sump opening directly into the space defined by said lower wall sections and spaced meditately of said sections and of said end walls, said lower sections having air inlet openings to direct streams of air to and immediately over said sump, and said upper sections having air inlet openings directing air inwardly and upwardly into the space between said upper sections and into said throat.

5. An oil burner in accordance with claim 4, characterized by said sump having a member extending into the space between the lower sections and having air inlet openings extending therethrough.

6. An oil burner in accordance with claim 4,

characterized by the lower sections having a lesser depth than said upper sections.

7. In an oil burner, a housing provided with a burner throat in the upper portion and having opposing elongated side walls and opposing end walls defining with a substantially flat bottom wall a combined vaporization and combustion chamber, said side walls having lower sections extending upwardly from said bottom in convergent relation and upper sections extending upwardly from said lower sections toward said throat in angular relation to said lower sections, means adapted to direct oil adjacent said bottom wall and into the space defined by said lower wall sections and mediately of said sections and of said end walls, said lower sections having air inlet openings to direct streams of air to and immediately over said means, and said upper sections having air inlet openings directing air inwardly and upwardly into the space between said upper sections and into said throat. 20
